[57] ABSTRACT

For the provision of automatic gauge control for the on line control of the delivery gauge of a workpiece passing through at least one roll stand of a tandem rolling mill, it is desired to establish the plasticity of each workpiece in relation to each roll stand of the rolling mill for the entire length of that workpiece from the head end of the workpiece to the tail end of the workpiece. The plasticity of each workpiece is established to provide a desired gauge control operation in relation to that one roll stand.

BACKGROUND OF THE INVENTION

The present invention relates to workpiece strip metal tandem rolling mills and more particularly to roll force gauge control systems and methods used in operating such rolling mills.

In the operation of a metal or steel reversing or tandem rolling mill, the unloaded roll opening and the speed at each tandem mill stand or for each reversing mill pass are set up to produce successive workpiece strip or plate reductions resulting in work product at the desired gauge. Generally, the loaded roll opening at a stand equals the stand delivery gauge or thickness on the basis of the usual assumption that there is little or no elastic workpiece recovery.

Since the operator provided initial roll opening setup conditions, or the initial roll opening settings provided by an associated digital computer control system operative with model equation information to calculate the setup screwdown schedules for the respective stands of the rolling mill, can be in error and since in any event certain mill parameters affect the stand loaded roll opening during rolling and after setup conditions have been established, a stand automatic gauge control system is employed if it is necessary that the stand delivery gauge be closely controlled. Thus, at the present state of the rolling mill art, and particularly the steel rolling mill art, a stand gauge control system is normally used for a reversing mill stand and for predetermined stands in tandem rolling mills.

The well known gaugemeter or roll force system has been widely used to produce stand gauge 1 in metal rolling mills and particularly in tandem hot steel strip rolling mills and reversing plate mills where experience has demonstrated that roll force control is particularly effective. Earlier publications and patents such as an

article entitled Installation and Operating Experience with Computer and Programmed Mill Controls by M. D. McMahon and M. A. Davis in the 1963 Iron and Steel Engineer Year Book at pages 726 to 733, an article entitled Automatic Gage Control for Modern Hot Strip Mills by J. W. Wallace in the December 1967 Iron and Steel Engineer at pages 75 to 86, U.S. Pat. No. 3,561,237 issued to Eggers et al. and U.S. Pat. 2,726,541 issued to R. B. Sims describe the theory

10 upon which operation of the roll force and related gauge control systems are based. Attention is also called to U.S. Pats. 3,568,637, 3,574,279, 3,574,280 and 3,600,920 issued to A. W. Smith, which relate to roll force automatic gauge control systems. In referencing prior art publications or patents as background herein, no representation is made that the cited subject matter is the best teaching prior art.

Briefly, the roll force gauge control system uses Hooke's law in controlling the screwdown position at a rolling stand, i.e. the loaded roll opening under workpiece rolling conditions equals the unloaded roll opening or screwdown position plus the mill stand spring stretch caused by the separating force applied to the rolls by the workpiece. To embody this rolling principle in the roll force gauge control system, a load cell or other force detector measures the roll separating force at each controlled roll stand and the screwdown position is controlled to balance roll force changes from a reference value and thereby hold the loaded roll opening at a substantially constant value. Hot strip mill automatic gauge control (AGC) including evaluation of roll force feedback information involves the combination of a number of process variables, such as roll force, screw position, and mill spring which are all used to evaluate the gauge of the strip as it is worked in each stand. In addition, an X-ray gauge is used on the strip as it passes out of the last stand to evaluate the absolute strip gauge produced.

40 The two gauge error detection systems that are commonly used are the X-ray and roll force. X-ray gauges can be placed between each stand, but they are expensive, difficult to maintain, and can detect errors only as the strip passes between stands. The roll force error detection system is much less expensive, and can be more easily implemented in relation to the operation of all stands, to detect errors in gauge as the strip passes between the rolls of a particular roll stand, providing immediate evaluation of desired corrections to the roll openings.

45 The roll force system, however, provides only a relative evaluation of the gauge, since it measures the amount of gauge deviation from a reference gauge, such as the gauge at the head end of the strip.

50 55 A practical combination of the two systems uses roll-force feedback to calculate fast corrections to fluctuations in gauge, and an X-ray gauge to evaluate the absolute gauge of the strip coming out of the last stand. The fast corrections are calculated from the roll force feed-

60 back, the stand screwdown position, and the modulus of elasticity of the rolling stand. The slower X-ray gauge evaluation calculates simultaneous corrections to several stands, so that the absolute value of the gauge may be brought to the desired value.

65 The output of both of these systems is a change in the position references supplied to the screwdowns of selected roll stands.

The following well known formula expresses the basic roll force gauge control relationship:

$$h = SD + F * K$$

(1)

where:

h = loaded roll opening (workpiece delivery gauge or thickness)

SD = unloaded roll opening (screwdown position)

K = stand mill spring constant

F = stand roll separating force.

Typically, the roll force gauge control system is an analog arrangement including analog comparison and amplification circuitry which responds to roll force and screwdown position signals to control the screwdown position and hold the following equality:

$$\Delta SD = -\Delta F * K$$

(2)

where:

ΔF = measured change in roll force from an initial force

ΔSD = controlled change in screwdown position from an initial screwdown position.

After the unloaded roll opening setup and the stand speed setup are determined by the mill operator for a particular workpiece pass or series of passes, the rolling operation is begun and the screwdowns are controlled to regulate the workpiece delivery gauge from the reversing mill stand or from each roll force controlled tandem mill stand. By satisfying Equation (2), and the assumptions implicit in Equation (1), the loaded roll opening h in Equation (1) is maintained constant or nearly constant.

As the head end of the workpiece strip enters each roll stand of the mill, the lock-on screwdown position LOSD and the lock-on roll separating force LOF are measured to establish what strip delivery gauge G should be maintained out of that roll stand. As the strip rolling operation proceeds, the roll stand separating force F and the roll stand screwdown position value SD are monitored periodically and any undesired change in roll separating force is detected and compensated for by a corresponding correction change in screwdown position. The lock-on gauge LOG is equal to the lock-on screwdown LOSD plus the lock-on force LOF multiplied by the mill stand spring modulus K . The workpiece strip delivery gauge G leaving the roll stand at any time during the rolling operation is in accordance with above equation (1) and is equal to the unloaded screwdown position SD plus the roll separating force F multiplied by the mill spring modulus K . The roll force determined gauge error GE in relation to a particular roll stand is derived by subtracting the lock-on gauge LOG from the delivery gauge G . The following Equations 3, 4 and 5 set forth these relationships.

$$LOG = LOSD + K * LOF$$

(3)

60

$$G = SD + K * F$$

(4)

65

$$GE = G - LOG = [SD - LOSD] + (F - LOF) * K$$

(5)

To provide steady state gauge error correction, the well known X-ray monitor gauge control system is usu-

ally employed to produce screwdown offset for the roll force control. In the monitor system, an X-ray or other radiation gauge sensing device is placed at one or more predetermined process points and usually at least at a process point following the delivery end after the last roll stand of the mill in order to sense actual delivery gauge after a workpiece transport delay from the point in time at which the actual delivery gauge is produced at the preceding stand or stands. The monitor system compares the actual delivery gauge with the desired delivery gauge and develops an X-ray gauge error as an analog feedback control signal to adjust the operation of the reversing mill roll force gauge control system or one or more predetermined tandem mill stand roll force gauge control systems to supply desired steady state mill delivery gauge. In this manner, the conventional monitor system provides for transport delayed correction of steady state gauge errors which are caused or which are tending to be caused by a single mill variable or by a combination of mill variables.

In operator controlled mills, some steady state gauge correcting operations can eventually be taken off the monitor system by screwdown recalibration, and the like, between similar workpiece passes if steady state gauge error tends to exist along the entire workpiece and persists from workpiece to workpiece. In this manner, some reduction is achieved in the length of off gauge workpiece material otherwise associated with monitor transport delay. Similarly, corrective monitor system operation caused by head end gauge errors can be reduced by changes in the operator or associated computer control system provided setup from workpiece to workpiece.

A background general teaching of stored program digital computer control system operation is set forth in a book entitled Electronic Digital Systems by R. K. Richards and published in 1966 by John Wiley and Sons.

An additional detailed description of computer programming techniques in relation to the control of metal rolling mills can be found in an article in the Iron and Steel Engineer Yearbook for 1966 at pages 328 through 334 entitled "Computer Program Organization for an Automatically Controlled Rolling Mill" by John S. Deliyanides and A. H. Green, and in another article in the Westinghouse Engineer for January 1965 at pages 13 through 19 and entitled "Programming for Process Control" by P. E. Lego.

A programmed digital computer system can be employed to make the gauge error correction screwdown movement determinations as well as to perform other mill control functions. The computer employs a programming system including an automatic roll force gauge control program or AGC program which is executed at predetermined periodic intervals to calculate the desired screwdown movement required at each roll force gauge controlled stand for gauge error correction including that stemming from roll force error detection at that stand.

SUMMARY OF THE INVENTION

In accordance with the broad principles of the present invention, a system and method for controlling workpiece delivery gauge in a metal rolling mill employs means for detecting gauge error in the workpiece delivered from a given roll stand, and means for controlling the screwdown position of at least that one roll-

ing stand of the mill in accordance with a predetermined relationship between said gauge error, the stand mill spring modulus and the workpiece plasticity for that stand, which plasticity is determined by calculation, for correcting the delivery gauge in relation to that given roll stand and this detected gauge error.

BRIEF DESCRIPTION OF THE DRAWINGS

FIG. 1 shows a schematic diagram of a tandem hot steel strip rolling mill and an automatic gauge control system arranged for operation in accordance with the present invention;

FIG. 2 illustrates the typical mill spring curve and workpiece reduction curve for a given rolling mill stand and the operation of that roll stand for reducing the gauge of a workpiece passed through the roll stand;

FIG. 3 illustrates, in relation to the mill spring curve and the workpiece reduction curve, the effect of a correction made to the screwdown position setting for changing the unloaded roll opening of a roll stand to provide a desired change in the workpiece gauge delivered from that roll stand.

FIG. 4 shows an illustrative gauge error detection operation in relation to the initial lock on conditions at the head end of the workpiece.

FIG. 5 shows a schematic illustration of the plasticity determination operation in accordance with the present invention.

DESCRIPTION OF THE GAUGE CONTROL SYSTEM AND ITS OPERATION

There is shown in FIG. 1 a tandem hot strip steel finishing mill 11 operated with improved gauge control performance by a process control system 13 in accordance with the principles of the invention. Generally, however, the invention is applicable to various types of mills in which roll force gauge control is employed.

The tandem mill 11 includes a series of reduction rolling stands with only two of the stands S1 and S6 shown. A workpiece 15 enters the mill 11 at the entry end in the form of a bar and it is elongated as it is transported through the successive stands to the delivery end of the mill where it is coiled as a strip on a down-coiler 17. The entry bar would be of known steel grade class and it typically would have a known input gauge or thickness of about 1 inch and a width within some limited range such as 20 inches to 80 inches. The delivered strip would usually have approximately the same width and a thickness based upon the production order for which it is intended.

In the reduction rolling process, the successive stands operate at successively higher speeds to maintain proper workpiece mass flow. Each stand produces a predetermined reduction or draft such that the total mill draft reduces the entry bar to strip with the desired gauge or thickness.

Each stand is conventionally provided with a pair of backup rolls 19 and 21 and a pair of work rolls 23 and 25 between which the workpiece 15 is passed. A large DC drive motor 27 is controllably energized at each stand to drive the corresponding work rolls at a controlled speed.

As previously described, the sum of the unloaded work roll opening and the mill stretch substantially defines the workpiece gauge delivered from any particular stand in accordance with Hooke's law. To vary the unloaded work roll opening at each stand, a pair of

screwdown motors 29 (only one shown at each stand) position respective screwdowns 31 (only one shown at each stand) which clamp against opposite ends of the backup rolls and thereby apply pressure to the work rolls. Normally, the two screwdowns 31 at a particular stand would be in identical positions, but they can be located in different positions for strip guidance during threading, for flatness or other strip shape control purposes or possibly for other purposes.

A conventional screwdown position detector or encoder 33 provides an electrical signal representation of screwdown position at each stand. To provide an absolute correspondence between the screwdown position and the unloaded roll opening between the associated work rolls, a screwdown position detection system which includes the screwdown position detector 33 can be provided and calibrated from time to time.

Roll force detection is provided at each of predetermined stands by a conventional load cell 35 which generates an electrical analog signal in accordance with the stand roll force. At the very least, each roll force controlled stand is provided with a load cell 35 and in many cases stands without roll force gauge control would also be equipped with load cells. The number of stands to which roll force gauge control is applied is predetermined during the mill design in accordance with cost-performance standards, and increasingly there is a tendency to apply roll force gauge control to all of the stands in a tandem hot strip steel mill. In the present case, a roll force gauge control system is assumed to be employed at each of the stands.

Conventional motorized sideguards 37 are located at predetermined points along the mill length. The sideguards 37 are operated during mill setup on the basis of the widths of the upcoming workpiece 15 thereby defining the sides of the workpiece travel path for guidance purposes.

The process control system 13 provides automatic control for the operation of the tandem mill 11 as well as desired control for associated production processes (not indicated) such as the operation of a roughing mill. The process control system 13 can include a programmed process control digital computer system which is interfaced with the various mill sensors and the various mill control devices to provide control over many of the various functions involved in operating the tandem mill 11. According to user preference, the control system 13, can also include conventional manual and/or automatic analog controls for selected process control functions.

On the basis of these considerations, automatic gauge control system 39 can include a digital computer system operative to provide the finishing mill on-line roll force gauge control function, such as a PRODAC 2000 (P2000) sold by Westinghouse Electric Corporation. A descriptive book entitled PRODAC 2000 Computer Systems Reference Manual has been published in 1970 by Westinghouse Electric Corporation and made available for the purpose of describing in greater detail this computer system and its operation.

There is disclosed in the above-referenced previously filed patent application Ser. No. 215,743 the logic flow chart of an illustrative automatic gauge control system suitable for operation with the plasticity determination operation of the present invention, for example at step 40 of the flow chart shown in FIG. 6A the plasticity is calculated. It should be readily understood by persons

skilled in this art that the present invention is also suitable for operation with other well known automatic gauge control systems where a determination of workpiece plasticity is desired for controlling the delivery gauge of a workpiece strip passed through at least one stand of a rolling mill.

The digital computer processor can be associated with well known predetermined input systems typically including a conventional contact closure input system which scans contact or other signals representing the status of various process conditions, a conventional analog input system which scans and converts process analog signals, and operator controlled and other information input devices and systems 41 such as paper tape teletypewriter and dial input systems. It is noted that the information input devices 41 are generally indicated by a single block in FIG. 1 although different input devices can and typically would be associated with the control system. Various kinds of information are entered into the control system through the input devices 41 including, for example, desired strip delivery gauge and temperature, strip entry gauge and width and temperature (by entry detectors if desired), grade of steel being rolled, plasticity tables, hardware oriented programs and control programs for the programming system, and so forth. The principal control action outputs from the automatic gauge control or AGC system include screwdown positioning reference commands which are applied to respective screwdown positioning controls 55 for operating the screwdown motors 29 for screw movement, and speed control signals which are applied to the respective speed and tension control system 53 to cause a change in drive speed to compensate for a change in thickness being made by a screwdown movement.

Display and printout devices 51 such as numeral display, tape punch, and teletypewriter systems can also be provided to keep the mill operator generally informed about the mill operation and in order to signal the operator regarding an event or alarm condition which may require some action on his part. The printout devices are also used to log mill data according to computer log program direction.

Generally, the AGC system uses Hooke's law to determine the total amount of screwdown movement required at each roll force controlled stand at the calculating point in time for roll force and gauge error correction, i.e., for loaded roll opening and stand delivery gauge correction to the desired value. The calculation defines the total change in the unloaded roll opening required to offset the gauge error causing condition.

During rolling operation, the on line gauge control system operates the stands to produce strip product having desired gauge and proper shape, i.e., flat with slight crown. On line gauge control is produced by the roll force gauge control loops at the stands and the previously noted X-ray monitor gauge control systems.

In the monitor system, the X-ray gauge 47 produces the X-ray gauge error or deviation signal which indicates the difference between actual strip delivery thickness and desired or target strip delivery thickness. In other cases, it may be desirable to employ an absolute thickness measurement X-ray gauge signal to form a basis for monitor control actions or, more generally, for screwdown offset control actions.

To effect on line gauge control in the closed loops, the AGC system operates at predetermined time peri-

ods such as every 2/10 second with the screwdown position detector and load cell provided signals from each stand as well as the X-ray gauge duration signal to determine the respective stand screwdown adjustment control actions required for producing desired strip delivery gauge.

In FIG. 2, linear approximations of the roll stand characteristic curves are shown to illustrate the application of Hooke's law to a rolling mill stand and to illustrate the basis upon which the on line gauge control system provides improved gauge control, accuracy and stability and other operating benefits. A mill modulus characteristic or mill spring curve 100 defines the separation between a pair of workpiece reducing mill stand work rolls as a function of separating force and as a function of screwdown position. The slope of the mill spring curve 100 is the well known mill spring modulus or constant K which is subject to variation as well known to persons skilled in this art. When a correct screwdown calibration is known and the screwdowns are positioned such that the empty work rolls are just facing, the unloaded screwdown zero position is defined. The workpiece deformation characteristic or reduction curve 102 is shown. The entry gauge H_E of the workpiece passed through the roll stand is reduced to the indicated delivery gauge H_D as defined by the intersection of the mill spring curve 100 and the product reduction curve 102 to establish the stand roll force required for the indicated operation. The unloaded roll opening, sometimes called the screwdown because of the screw-and-nut system used for adjusting the roll opening, is the gauge that would be delivered if there were no roll separating force. As the force increases with a constant roll opening, the delivery gauge increases, since the mill deflects as shown by the mill spring curve 100. If no force was exerted on the product being rolled, the gauge would not be reduced and the delivery gauge would be equal to the entry gauge. When the roll force increases, the product is plastically deformed and the delivery gauge decreases. The slope of the mill spring characteristic line is called the mill modulus (K) and the slope of the product reduction characteristic is called the product plasticity (P). The delivery gauge is determined by the equilibrium point at which the force exerted by the mill is equal to the force required to deform the product. Changes in entry gauge and product hardness result in a change in roll force and delivery gauge. The automatic gauge control moves the screwdown to correct for these gauge changes. The main advantage of the roll force gauge control system is its ability to detect changes in gauge the instant they take place, as the product is being rolled in the stand. A shift in delivery thickness can be caused by a change in entry thickness or a change in hardness (usually caused by a change in temperature). This change in delivery gauge is immediately detected by monitoring the roll separating force of the roll stand.

When the screwdowns are opened (positive movement) the unloaded roll opening increases as reflected by a change to the right in the graphical location of the mill spring curve 100 such that the theoretical spring curve intersect equals the new unloaded roll opening. With screwdown closing, the mill spring curve is shifted to the left in a similar manner.

At any particular screwdown position and with correct screwdown calibration, the stand workpiece deliv-

ery gauge H_D equals the unloaded roll opening as defined by the screwdown position SDREF plus the mill stretch (F^*K) caused by the workpiece. If the screwdown calibration is incorrect, i.e., if the number assigned to the theoretical roll facing screwdown position is something other than zero because of roll crown wear or other causes, the stand workpiece delivery gauge H_D then equals the unloaded roll opening plus the mill stretch, plus or minus the calibration drift.

The amount of mill stretch depends on the product deformation characteristic or reduction curve 102 for the workpiece as shown in FIG. 2, the reduction curve 102 for a strip of predetermined width represents the amount of force F required to reduce the workpiece from the stand entry gauge (height) H_E . The workpiece plasticity P is the slope of the curve 102, and the curve 102 is shown as being linear although a small amount of nonlinearity would normally exist.

Desired workpiece delivery gauge H_D is produced since the amount of force F required to reduce the workpiece from H_E to H_D is equal to the amount of roll separating force required to stretch the rolls to a loaded roll opening H_D , i.e., the intersection of the mill spring curve 100 at an initial screwdown opening SDREF indicated by mill spring curve 100 and the workpiece reduction curve 102 lies at the desired gauge value H_D .

As shown in FIG. 3, if the actual stand present gauge H_x is not the same as the desired gauge H_D , there is a gauge error GE to be corrected. This condition can be corrected by changing the provided screwdown position reference SDREF to the stand, such that a new mill spring curve 104 becomes operative to result in the desired gauge H_D being delivered from the roll stand and the gauge error GE is now removed.

It is known in accordance with the teachings of above referenced U.S. Pat. No. 3,561,237 that the required corrective screwdown adjustment ΔSD to correct a stand delivery gauge error GE is equal to the product of that gauge error GE times the sum of the ratio of the workpiece plasticity P for that same stand with the mill spring modulus K for that same stand and one, as follows in relation to stand (N):

$$\Delta SD(N) = \text{exit } GE(N) * [P(N)/K(N) + 1] \quad (6)$$

In the teachings of the latter patent, the mill spring constant $K(N)$ was defined in terms of millions of pounds of roll force per inch of screwdown position change. The workpiece plasticity $P(N)$ was similarly defined. It has been established in relation to the practice of the present invention that these values are preferred in terms of inches of screwdown position change per millions of pounds of roll force. Thusly, the above equation (6) will be rewritten and utilized in accordance with the relationship:

$$\Delta SD(N) = \text{exit } GE(N) * [K(N)/P(N) + 1] \quad (7)$$

The stand N exit gauge error determined by the roll force system at stand (N) is established by the relationship of above equation (5) as follows:

$$GE(N) = [SD(N) - LOSD(N)] + [F(N) - LOF(N)] * K(N) \quad (8)$$

In reference to FIG. 4, in general the workpiece strip gauge error delivered by a given stand, and as determined by the sensed operational variable at that same stand, is in accordance with the roll force system relationship shown in above equation (8). The exit gauge error leaving stand (N), for example, equals the sum of a first quantity, which is the difference between the presently measured screwdown position $SD(N)$ and the initial lock on screwdown position $LOSD(N)$, and a second quantity, which is the determined mill spring modulus $K(N)$ times the difference between the presently measured roll separation force $F(N)$ and the initial lock on roll force $LOF(N)$.

15 DESCRIPTION OF EMBODIMENT OF PRESENT INVENTION

In general, the plasticity $P(N)$ of a workpiece strip in relation to roll stand (N) of a rolling mill is a function of the strip width, temperature, gauge and hardness.

20 The plasticity $P(N)$ for typical roll stand (N) must be accurately determined in order to remove and correct by screwdown adjustment at stand (N) the delivery gauge error it is desired to correct at stand (N). For this purpose, the present control system including the digital computer is operative to calculate the plasticity of the workpiece strip at each roll stand every 0.2 second. Since the workpiece plasticity is a measure of the change in thickness caused by a compressive roll force, it is calculated by the following relationship:

$$P(N) = \text{Draft } (N)/\text{Force } (N) \quad (9)$$

$$P(N) = \text{Entry gauge } (N) - \text{Exit gauge } (N)/\text{Roll force } (N) \quad (10)$$

Since the entry gauge to stand (N) is equal to the exit gauge leaving previous roll stand (N-1), the following relationship can be established:

$$\text{Exit gauge } (N-1) = \text{Entry Gauge } (N) \quad (11)$$

This permits the following modification of above equation (10) for plasticity:

$$P(N) = \text{Exit gauge } G(N-1) - \text{Exit gauge } G(N)/\text{Roll Force } F(N) \quad (12)$$

The following workpiece volume mass flow relationship between the stand speeds and delivery gauges must be provided for proper passage of a workpiece through the plural stands of a tandem rolling mill:

$$G(I)*S(I) = G(N)*S(N) = G(LS)*S(LS) \quad (13)$$

Where:
 $G(I)$ is the delivery gauge leaving the first roll stand

60 $S(I)$ is the operating speed of the first roll stand

$G(N)$ is the gauge leaving stand (N)

$S(N)$ is stand (N) operating speed

$G(LS)$ is the last stand delivery gauge

$S(LS)$ is the last stand operating speed.

65 Since the X-ray device positioned after the last stand is operative to measure the last stand delivery gauge $XG(LS)$, the following relationships can be established:

$$G(N) = XG(LS) * [S(LS)/S(N)] \quad (14)$$

$$G(N-1) = XG(LS) * [S(LS)/S(N-1)] \quad (15)$$

Using the well known mass flow relationship set forth by above equation (13). Now if the quantities of equations (14) and (15) are substituted into above equation (12), the following relationship for plasticity $P(N)$ at stand (N) will result:

$$P(N) = \frac{XG(LS) * \left[\frac{S(LS)}{S(N-1)} \right] - XG(LS) * \left[\frac{S(LS)}{S(N)} \right]}{F(N)} \quad (16)$$

The latter equation can be rearranged as follows:

$$P(N) = [XG(LS) * S(LS)/F(N)] * [1/S(N-1) - 1/S(N)] \quad (17)$$

The width of the workpiece strip passing through the roll stands of a tandem rolling mill is assumed to remain substantially constant for the purpose of the determination of workpiece plasticity for each stand of the rolling mill.

In reference to FIG. 5, there is shown a portion of a tandem rolling mill including the last roll stand (LS), an earlier roll stand (N) and then a previous roll stand (N-1), with the workpiece strip 15 moving in the direction indicated by the arrow. The X-ray device 500 provides an X-ray gauge deviation in relation to absolute gauge error leaving stand (LS). At block 502 the desired gauge reference is added to the X-ray deviation such that the actual X-ray measured gauge XG(LS) is supplied to block 504. At block 504 the plasticity $P(N)$ for stand (N) is calculated using above equation (17). At block 506 the exit gauge error $G(N)$ leaving stand (N) is calculated in relation to above equation (5), with the understanding that block 506 includes a memory function such that the lock on values of the screwdown LOSD(N) and the roll force LOF(N) are remembered as required in this regard. At block 508 there is deter-

mined the stand (N) screwdown position correction SD(N) required to remove this same stand (N) gauge error, and this utilizes above equation (7) for this purpose.

The typical AGC control program is written as a loop operation such that one set of coding processes all of the roll stands, and every time the program operates through the loop a calculation is made when appropriate for each of the roll stands in relation to the gauge error and the plasticity determination for adjusting each roll stand screwdown position as desired to correct the delivery gauge error at that roll stand.

GENERAL DESCRIPTION OF INSTRUCTION PROGRAM LISTING

In the Appendix there is included an instruction program listing that has been prepared to control the roll force automatic gauge control operation of a tandem rolling mill in accordance with the here disclosed control system and method. The instruction program listing is written in the machine language of the PRODAC P2000 digital computer system, which is sold by Westinghouse Electric Corporation for real time process control computer applications. Many of these digital computer systems have already been supplied to customers, including customer instruction books and descriptive documentation to explain to persons skilled in this art the operation of the hardware logic and the executive software of this digital computer system. This instruction program listing is included to provide an illustration of one suitable embodiment of the present control system and method that has actually been prepared. This instruction program listing at the present time has been partially debugged through the course of practical operation for the real time automatic gauge control of a tandem rolling mill, but it is understood and well known by persons skilled in this art that most real time process control application programs contain some bugs or minor errors, and it is within the routine skill of such persons and takes varying periods of actual operation time to identify and correct the more critical of these bugs.

TTL AUTOMATIC GAUGE CONTROL

MODIFIED: 1/26/72

THIS PROGRAM CONTROLS THE GAUGE OF THE MILL BY THREE PROCESSES:
 DIRECT ACTION BASED ON ROLL FORCE
 CALCULATIONS OF THE GAUGE ERROR,
 FEED FORWARD TO HANDLE SKID MARKS,
 AND FEED BACK TO HANDLE STANDS WHICH
 GO OUT OF LIMITS. THE PROGRAM ALSO
 OUTPUTS A CORRECTION TO THE LOOPERS.

What we claim is:

1. A gauge control system for a rolling mill having at least a first roll stand and a second roll stand operative to reduce the gauge of a workpiece passed through said rolling mill and including a device for measuring the gauge of said workpiece leaving the rolling mill, said system comprising:

means for determining the plasticity of said workpiece for each of a plurality of segments along the length of said workpiece in relation to said second roll stand in accordance with a predetermined relationship including for each of said workpiece segments said measured gauge of said workpiece, a first speed related to the workpiece, speed leaving said first roll stand, a second speed related to the workpiece speed leaving said second roll stand and the roll force of said second roll stand, and means for controlling the roll opening of said second roll stand for each of said workpiece segments during the passage of said workpiece in accordance with said plasticity determined for the same workpiece segment.

2. The gauge control system of claim 1, with said plasticity being determined for each said workpiece segment in accordance with the relationship:

$$P(N) = [XG(LS) * S(LS)/F(N)] * [1/S(N-1) - 1/S(N)]$$

Where $P(N)$ is the determined plasticity, where $XG(LS)$ is the measured gauge, where $S(LS)$ is related to the speed of the workpiece leaving the rolling mill, where $F(N)$ is the roll force of the second roll stand,

where $S(N-1)$ is said first speed, and where $S(N)$ is said second speed.

3. The gauge control system of claim 1, with said means for controlling the roll opening of said second roll stand for each of said workpiece segments being operative in accordance with the relationship:

$$\Delta SD(N) = GE(N) * [K(N)/P(N) + 1]$$

where $\Delta SD(N)$ is the adjustment to be made in the roll opening of said second roll stand, where $GE(N)$ is the gauge error of the workpiece leaving said second roll stand, where $K(N)$ is the mill spring modulus of the second roll stand, and where $P(N)$ is the determined plasticity.

4. A method of controlling the workpiece gauge leaving a rolling mill having at least a first roll stand followed by a second roll stand and being operative to re-

duce the gauge of a workpiece passed through said rolling mill and in relation to a measured gauge of said workpiece leaving said rolling mill, the steps of said method comprising:

5 determining the plasticity of said workpiece for each of a plurality of workpiece segments along the length of said workpiece in relation to said second roll stand in accordance with said measured gauge, the roll force of said second stand and the speed of said workpiece in relation to each of said first and second roll stands,

10 determining the gauge error for each of said workpiece segments of said workpiece leaving said second roll stand,

15 determining a correction for application to said second roll stand in relation to each of said workpiece segments during the passage of said workpiece in accordance with a predetermined relationship between said gauge error and said plasticity of said first workpiece, and

20 controlling the operation of said second roll stand in relation to each of said workpiece segments in accordance with said correction.

25 5. The method of claim 4 with said plasticity for each of said workpiece segments being determined in accordance with the relationship:

$$P(N) = [XG(LS) * S(LS)/F(N)] * [1/S(N-1) - 1/S(N)]$$

where $P(N)$ is the determined plasticity, where $XG(LS)$ is the measured gauge, where $S(LS)$ is related to the speed of the workpiece leaving the rolling mill, where $F(N)$ is the roll force of the second roll stand,

35 where $S(N-1)$ is related to the speed of the workpiece leaving the first roll stand, and where $S(N)$ is related to the speed of the workpiece leaving the second roll stand.

40 6. The method of claim 4, with said correction for each of said workpiece segments being determined in accordance with the relationship:

$$\Delta SD(N) = GE(N) * [K(N)/P(N) + 1]$$

45 where $\Delta SD(N)$ is the correction, where $GE(N)$ is the gauge error for each segment of the workpiece leaving the second roll stand, where $K(N)$ is the mill spring modulus of the second roll stand, and where $P(N)$ is the determined plasticity for each workpiece segment.

UNITED STATES PATENT OFFICE
CERTIFICATE OF CORRECTION

Patent No. 3,798,941 Dated March 26, 1974

Inventor(s) Richard Q. Fox

It is certified that error appears in the above-identified patent and that said Letters Patent are hereby corrected as shown below:

In the claims: claim 2, column 47, line 26, change "1/S(N-1) - 1/S(N)]" to -- [1/S(N-1) - 1/S(N)]--.

Claim 3, column 47, line 41, change "[K(N)/P(N) + 1]" to -- [K(N)/P(N) + 1]--.

Claim 5, column 48, line 28, change "1/S(N)]" to -- 1/S(N)] --.

Claim 6, column 48, line 43, change "[K(N)/P(N)+1]" to --[K(N)/P(N)+1] --.

Signed and sealed this 22nd day of October 1974.

(SEAL)
